[57] **CLAIM**

The ornamental design for a roman numeral electro-optical display, as shown and described.

DESCRIPTION

FIG. 1 is a face view of the basic character and the font formed therefrom of a roman numeral electro-optical display showing my new design;

FIG. 2 is a face view of the basic character of the font formed therefrom of a roman numeral electro-optical display showing a modified form of my new design; and
FIG. 3 is a face view of the basic character and the font formed therefrom of a roman numeral electro-optical display showing another modified form of my new design.

FIG. 1

FIG. 2

FIG. 3
